UNITED STATES PATENT OFFICE

134,638

DESIGN FOR A MUFFLER OR SIMILAR ARTICLE

Joseph Melville, Long Beach, N. Y.

Application October 14, 1942, Serial No. 108,518

Term of patent 7 years

To all whom it may concern:

Be it known that I, Joseph Melville, a citizen of the United States of America, residing in Long Beach, county of Nassau, and State of New York, have invented a new, original, and ornamental Design for a Muffler or Similar Article, of which the following is a specification, reference being had to the accompanying drawing, forming part thereof, wherein,

The figure of the drawing is a plan view of a muffler or similar article showing my new design.

I claim:

The ornamental design for a muffler or similar article, substantially as shown.

JOSEPH MELVILLE.
